UNITED STATES PATENT OFFICE.

FRANK COZZOLI, OF PLAINFIELD, NEW JERSEY.

FRUIT-PRESS DRIVE.

Application filed November 16, 1925. Serial No. 69,442.

To all whom it may concern:

Be it known that I, FRANK COZZOLI, a citizen of the United States, and a resident of Plainfield, in the county of Union and State of New Jersey, have invented a new and Improved Fruit-Press Drive, of which the following is a full, clear, and exact description.

This invention relates to fruit press drives and has for an object to provide an improved construction which may be readily used for large or small fruit presses and which will secure a maximum pressing effect with a minimum effort.

Another object of the invention is to provide a drive for fruit presses wherein both power and manually actuated means are provided for operating the device.

A further object of the invention is to provide a fruit press drive wherein a spring is interposed between the pressing disk and the driving mechanism for maintaining the pressing disk under tension after the driving mechanism has stopped.

A still further object, more specifically, is to provide a fruit press drive wherein an electric motor is used for operating the moving parts, the same being associated with an automatic switch mechanism for throwing the current on and off until a maximum pressing effect has been secured.

In the accompanying drawing—

Figure 1 is a fragmentary top plan view of a fruit press drive disclosing an embodiment of the invention.

Figure 2 is a sectional view through Figure 1, approximately on line 2—2.

Referring to the accompanying drawing by numerals, 1 indicates a tub or container which may be of any desired construction, preferably of a number of vertical slats or bars whereby the juices from the fruits may freely flow therebetween. Associated with the tub 1 is a screw shaft 2 which is held stationary by the base of the device or in any desired manner. As the tub 1, screw 2, base and other parts form no part of the present invention except in combination, further description will not be given. A presser disk 3 is loosely arranged in the tub 1 and is acted upon by the presser foot 4 which in turn is caused to function by the spring 5 which is very strong. This spring at the lower end presses against the foot 4 and at the upper end against what may be termed the driving casing 6. This casing is provided with an

annular groove 7 in which the annular flange 8 of hub 9 is loosely fitted. The hub 9 is preferably formed integral with the worm wheel 10 though it could be made separate and rigidly secured thereto. The hub 9 is internally threaded and screws onto the threaded shaft or screw 2 as clearly shown in Figure 2. A worm 11 meshes continually with wheel 10, said worm being supported and driven by the shaft 12 which is supported in suitable bearings in the casing 6, which casing extends upwardly and is formed with an annular flange 13 to which is bolted or otherwise secured a plate 14. The shaft 12 may be rotated manually by a handle or crank 15 or may be rotated by an electric motor 16 as hereinafter fully described. It will be noted that the casing 6 is provided with an annular tubular extension 17 having ears 18 through which the respective bolts 19 extend. These bolts are screwed into the foot 4 but loosely pass through the ears 18. By this construction and arrangement, the spring 5 will hold the tubular member 17 out of contact with the foot 4 during the first part of the pressing action but as the fruit becomes more and more compact, the spring 5 will be gradually compressed or closed and will be completely closed by the time the lower end of the tubular member 17 strikes the tubular projection 20 of foot 4. As the spring 5 gradually compresses, the ears 18 will move away from the respective nuts 21 but the bolts 19 will continue to guide the parts. An insulating support 22 is riveted or otherwise secured to the tubular member 17 and supports a switch for motor 16. This switch includes a swinging arm 23 pivotally mounted at 24 on the insulating member 22. A pin 25 extends into the opening 26 in the upper end of bracket 27, said bracket being riveted or otherwise secured to the foot 4. Wire 28 extends from one terminal of motor 16 to the contact 29 while wire 30 extends from the source of power which drives the motor 16. It will be noted that the second contact of motor 16 will also extend to the source of power so that when the parts are in the position shown in Figure 2 current will be turned on to motor 16. It is evident that a manually actuated switch could be interposed in the circuit at any point in addition to the switch shown in Figure 2.

When the tubular member 17 moves downwardly until it contacts or almost contacts

with the tubular extension 20, pivot 24 will also be moved downwardly and, consequently, will swing the contact arm 23 until the spring 31 can shift the same quickly over 5 to the opposite extreme position, as for instance, that shown in dotted lines in Figure 2. The contact 29 is adapted to extend over arm 23 and remain in contact therewith until the arm is quickly shifted by spring 31 10 so that the current from motor 16 is turned off automatically at approximately the time when the spring 5 is fully compressed. The current will remain turned off until spring 5 gradually forces the parts downwardly until 15 spring 31 can again flop the arm 23 over into engagement with contact 29. When this occurs the parts will again be operated for compressing spring 5. This compressing action will continue until the spring has 20 been completely compressed and spring 31 will a second time, move arm 23 out of engagement with contact 29. If the matter being compressed yields sufficiently, this action will be repeated again but if it does not 25 yield sufficiently, the current will remain turned off and the spring 5 will remain under great compression. In this way, an almost perfect squeezing action is given to the fruits so that all of the juices may be extracted. When squeezing grapes, apples or 30 other fruits, it requires time to allow the juices to move out of the pulp and by using the spring 5, ample time is allowed for the juices to run out of the fruits without the 35 necessity of the workmen watching the apparatus. The motor 16 may be connected up to the driving shaft 12 in any desired manner.

In the accompanying drawing, a gear 40 wheel 32 is rigidly secured to shaft 12 and extends through a suitable aperture 33 in the plate 14 so that it may continually mesh with a pinion 34. The pinion 34 continually meshes with a pinion 35 rigidly secured 45 to the shaft 36 and a pulley wheel 37 is rigidly secured to shaft 36 and accommodates the belt 38 which passes over pulley 39 secured to the shaft 40 connected with the armature of the motor 16. Suitable brackets 50 41 and 42 are connected with plate 14 and present means for supporting the shaft 36 and also the stub shaft 43.

What I claim is:

1. A fruit press drive, comprising a stationary threaded shaft, a traveling nut arranged on said shaft, means including an electric motor for rotating said nut, a spring

compressed by said nut when the same is rotated in one direction, a shoe for transmitting the pressure of said spring, and an 60 automatically actuated switch arranged in the circuit of said motor, said switch being automatically opened when said spring is completely compressed and automatically closed when said spring is partly distended. 65

2. A fruit press drive, comprising a presser shoe, a spring acting on said presser shoe, a housing acting on said spring, a stationary threaded shaft, a nut carried by said housing and mounted on said shaft, 70 means for rotating said nut for moving said housing whereby when said nut is moved in one direction said housing will compress said spring and cause said shoe to function, means including an electric motor for rotating said nut, a switch carried by said housing interposed in the circuit of said motor, and means carried by said shoe for automatically opening and closing said switch according to the position of the housing 75 in respect to the shoe.

3. A fruit press drive, comprising a presser foot and driving mechanism for causing said foot to function, said driving mechanism including an electric motor, a 80 plurality of rotating members operated by said motor, a spring interposed between said foot and certain of said rotating members for transmitting power from the rotating members to the foot and for causing the foot to function after said rotating members have stopped their rotation and automatically actuated means for opening the circuit of said motor when said spring has been fully compressed and again close said circuit when 85 the spring is partly released.

4. A fruit press drive, comprising a presser foot, a spring acting on said presser foot, a housing acting on said spring for compressing the same, a traveling nut acting on said housing for causing the housing to compress said spring, a worm wheel secured to said nut, a worm continually meshing with said wheel, a train of gears connected with said worm, a pulley connected with one member of said train of gears, a belt connected with said pulley, a motor including a pulley for moving said belt, and means carried by said foot and said housing for automatically turning off the current to 100 said motor when said spring has been compressed to a certain point.

FRANK COZZOLI.
